UNITED STATES PATENT OFFICE.

WILLIAM C. BAESEL, OF PROVIDENCE, RHODE ISLAND.

WASHING-MACHINE.

1,394,267.

Specification of Letters Patent. Patented Oct. 13, 1921.

Application filed May 5, 1921. Serial No. 466,955.

To all whom it may concern:

Be it known that I, WILLIAM C. BAESEL, a citizen of the United States, residing at Providence, in the county of Providence and 5 State of Rhode Island, have invented new and useful Improvements in a Washing-Machine, of which the following is a specification.

This invention relates to certain new and 0 useful improvements in a washing machine and it has for its object to provide an improved mechanism for imparting a combined rotary and reciprocatory motion to the clothes pounder whereby the point of 5 contact of the latter with the clothes will constantly and automatically be changing.

The invention consists in a vertically reciprocatory pounder carrier having a slide- 0 connection with a rotary drive member, and improved means for concurrently operating the rotary drive member and imparting a reciprocatory motion to the pounder carrier.

Further the invention resides in the features of construction and the novel arrangements and combinations of parts hereinafter described and claimed, reference being made to the accompanying drawings wherein:

Figure 1 is a plan view of a washing machine embodying the present improvements;

Fig. 2 is a side elevation thereof;

Fig. 3 is a vertical section therethrough from a point of view disposed ninety degrees from the view point of Fig. 2;

Fig. 4 is a detailed horizontal section on line 4-4 through Fig. 3; and

Fig. 5 is a fragmentary perspective view of the rotary drive for the pounder.

Referring more in detail to the accompanying drawings, the tub or clothes container 1 is mounted on a frame consisting of a table 2 supported on legs 3 which latter extend above the former and embrace the sides of the tub. The bottom of the tub is centrally apertured to receive a tubular bearing or hub 4 extending from the underlying table or shelf, and on this upwardly protruding bearing 4 is threaded the lower end of a spring housing 5 which seats on suitable packing as shown.

The pounder comprises a pair of inverted cups 6 of flaring designed to work down and up on the clothes to alternately force and draw in the washing fluid through the same, said cups having shanks 7 slidably mounted on the ends of the cross bar 8 and

yieldably held in their normal, lower position by means of the coiled springs 9 compressed between the cross bar and nuts 10 adjustable on the shanks. A shaft 11 is slide- 60 able through a cap 12, on the housing 5, through the latter and also through the bearing 4, the same projecting a distance beneath the table 2 and having a swivel yoke 13 secured thereto. Journaled in a pair of 65 brackets or standards 14, depending from the table, is a shaft 15 which has fixed thereon a gear 16 and a strap wheel 17, and to the latter is anchored an end of a strap 18 which passes around the wheel and has its opposite 70 end connected to the yoke 13 so that when the shaft is revolved to wind the strap on its wheel the slideable vertical shaft will be pulled down and when the shaft 15 is re- 75 volved in the opposite direction the strap will be slackened to permit the return of the pounder to its normal, elevated position. This return is effected by a plurality of coiled compression springs 19 arranged within the housing 5. 80

A horizontal drive shaft 20 is journaled in bearings 21 and has fixed thereon a gear 22 in mesh with but larger than gear 16, and also adjustably fixed on this shaft is an arm 23 having ledge 24 on its upper, free 85 end for pivotally supporting a pawl 25 that is normally held against a stop pin by a spring 26. The pawl is designed to engage a ratchet wheel 27 which is splined on the vertical shaft 11 and is retained in position 90 by a bracket 28 mounted on the underside of the table, said ratchet being held against retrograde movement by a pawl 30.

In operation, power is applied in an oscillatory manner to the shaft 20, as by a hand lever 29 fixed thereon, and this power being transmitted direct to the pawl-carrying arm 23 imparts an intermittent or step-by-step rotation to the vertical shaft and its supported pounder-cups. Concurrent with this 95 operation the larger gear 22 drives the smaller gear 16 with an oscillatory motion to effect an alternate winding and an unwinding of the strap which in turn vertically reciprocates the pounder-cups with the 100 assistance of the springs 19. Thus, this simple mechanism imparts an intermittent rotary motion combined with an up and down movement to the cups which enables a thorough washing of the clothes contents of the 105 tub.

Having thus described my invention,

what I claim as new and desire to secure by Letters Patent is:—

1. In combination with a driving shaft and a rotatable and vertically movable member having a ratchet thereon, a pawl carrying arm on the shaft, having the pawl thereof engaged with the ratchet to operate the latter, a yoke swiveled on said member, a wheel, a flexible connection between the yoke and wheel for winding upon the latter, a driving connection between the shaft and wheel, and means to oscillate the driving shaft.
2. In combination with a vertically slideable spring pressed shaft, a ratchet splined thereon, means to hold the ratchet against vertical movement, the shaft extending beyond said means, winding means connected to the shaft extension to move same downwardly against the tension of the spring, and combined means to wind said means and to engage the ratchet and effect step by step rotation thereof.
3. In combination with a vertically slideable spring pressed shaft, a ratchet splined thereon, means to hold the ratchet against vertical movement, the shaft extending beyond said means, winding means connected to the shaft extension to move same downwardly against the tension of the spring, a driving shaft, a connection between the driving shaft and the winding means to operate the latter, an arm on the driving shaft having a pawl engaging the ratchet and means to oscillate the driving shaft.
4. In combination with a vertically movable spring pressed shaft, means to rotate the shaft, means to hold the rotatable means against vertical movement, rotatable means to move the shaft downwardly against the tension of the spring, driving means and combined means to actuate said third means and to engage the first means to effect step-by-step rotation of the spring pressed shaft.
5. In combination with a shaft, a ratchet splined on the shaft and beyond which the shaft extends, a yoke swiveled on the shaft extension, a second shaft, a wheel mounted on the second shaft, a flexible connection between the wheel and yoke for winding upon the former when the shaft is rotated to impart a reciprocatory movement to the first shaft, a drive shaft geared to the second shaft, an arm fixed on the drive shaft, a pawl pivoted on the outer end of the arm for engaging the ratchet to partially rotate the same, and a hand lever fixed on the drive shaft.
6. In combination with a shaft, spring means for holding the shaft elevated, a rotatable shaft, a wheel fixed thereon, and a flexible member windable about the wheel and swivelly connected to the shaft.

In testimony whereof I have signed my name to this specification in the presence of two subscribing witnesses.

WILLIAM C. BAESEL.
